GARMENT STRETCHING AND PRESSING DEVICE

Harry D. Forse, Anderson, Ind.

Application November 29, 1945, Serial No. 631,618

24 Claims. (Cl. 223—57)

1

This invention relates to a press structure for shirts and other garments and, by way of illustration, it may be adapted for trouser pressing, etc. Herein, however, it is illustrated, by way of example only, as embodied in a shirt or like press.

The chief object is to provide a buck or the like upon which a shirt may be placed and when placed, it is stretched or smoothed and when devoid of wrinkles it is pressed or ironed both front and back, as well as creased for folding, and between cooperating, heated, cavity providing heads.

One chief feature of the present invention resides in applying ironing pressure to the garment by buck expansion in the head cavity.

A further chief feature of the invention resides in the automatic sequence of operations and the interlocking relationship therebetween.

Another feature of the present invention resides in applying transverse pressure to a garment to stretch same.

Other objects and features of the invention will be set forth more fully hereinafter.

The full nature of the invention will be understood from the accompanying drawings and the following description and claims:

In the drawings

Fig. 1 is a front elevation of the buck with a shirt omitted therefrom.

Fig. 2 is a transverse sectional view of such buck.

Fig. 3 is an end elevation of the major portions of the press in a partially open position.

Fig. 4 is a similar view with parts in the closed or pressing position, parts being broken away to show same and other parts in section.

Fig. 5 is a diagrammatic elevational view illustrating the several parts and the interlocks associated therewith, the envelope being omitted.

Fig. 6 is a vertical sectional view taken on line 6—6 of Fig. 5 and in the direction of the arrows.

Fig. 7 is a schematic or diagrammatic elevational view of the press controls.

Fig. 8 is a schematic or diagrammatic view of the three valve mechanisms in the normal position wherein the press is locked closed.

Fig. 9 is a similar view of the same valve system and corresponding to when the buck is in exposed or elevated position for garment application and removal.

In Fig. 1 of the drawings 10 indicates an elongated fairly thin bar member with rounded corners 10a. Extending upwardly therefrom are two parallel tubes or cylinders 11 which are

2

closed at their upper ends at 11a. Within each tube 11 and positioned near the upper end is a centrally ported piston 12 carried by tubular rod 13 which extends through and is slidably associated with bearing 14 in the bar member 10 or more specifically in the cylinder 11 at the lower end thereof.

Extending upwardly from plate 110 are ears 15 which pivotally support the inturned angular ends 16 of tubular rods 13, same having a common connection to a pressure supply and release line 17. It will be obvious that when pressure is applied to the two cylinders which are cross-connected at 18, the bar member 10 is raised relative to plate 110 and when the pressure is released the plate is positioned as shown in Fig. 1. This corresponds to the pressing position while the buck elevated position corresponds to the garment laying or applying and removing position.

Pivoted at 19 on the cylinders are two links 20 directed outwardly. Pivoted at 21 on the cylinders are two links 22 which have their adjacent inner ends pivoted together at 23 and to a slide member 24. To the outer ends of links 20 and 22 at 25 and 26, respectively, are pivotally connected the members 28 and carried thereby are the elongated wire members 27 with inturned curved ends 27a.

30 A spring 29 is interposed between each of the links 20 and the bar member 10 and these springs accordingly tend to draw the wire members 27 inwardly towards one another. When plate 24 connected to links 22 is depressed the members 21 are caused to separate laterally in opposition to springs 29.

Near the upper end of this buck structure are two outwardly and downwardly inclined members 30 broadly similar to members 27—28. Extending across the upper portions of cylinders 11 and secured thereto is the plate 31, see Figs. 1, 2 and 6. Secured to plate 31 is the collar form member 32, see Figs. 1, 5 and 6, which is hollow or chambered as at 33, see Fig. 5.

40 Extending forwardly from members 30 are arms 34, see Fig. 5, which have angular extensions 35 mounting pins 36 in their lower inner ends. Carried by form member 32, and if desired by plate 31 as well, is a shaft 38, see Figs. 4 and 6, 50 rigid with which, in chamber 33, is a cam member 39. A crossbar 40, see Fig. 5, has tangential contact with cam 39.

The crossbar 40 has an oppositely directed spring centering projection 41 seating in one end 55 of a compression spring 42. The collar form 32 at

43 has a similar projection seating in the opposite end of said spring 42. This spring normally tends to force crossbar 40 upwardly and is compressed when the shaft 38 is rotated and the crossbar is forced downwardly by the cam 39.

The lower adjacent ends of arms 35 mount pins 36 that ride in longitudinally directed slots 45 in the ends of the crossbar 40. All of the aforesaid mechanism is enclosed in the collar form aforesaid. Shaft 38 is tubular and mounts hand-wheel 46, see Figs. 5 and 6. As the hand-wheel is turned from the cam lowered position, the spring forces crossbar 40 upwardly for outward and upward projection of members 30. Obviously a reverse power application may be employed when desired, that is, spring means may be used to retract members 30 while cam 39 would be utilized to force said members 30 upwardly.

Extending through tubular shaft 38 and into the buck is a shaft 47 which on its outer end mounts a hand-wheel 48 which shaft on its inner end mounts a cam member 49. This cam engages roller or follower 50 carried by slide or plate 24. This is the side extension control plate. The latter may be slotted longitudinally as at 51 and a follower 52, carried by said plate 31, rides in said slot 51.

As noted, see Fig. 1, two longitudinally aligned slots are provided and two pin followers 52 are provided. For convenience, same are disposed upon plates 24 and 31 respectively, as illustrated, but they may be reversed. This dual connection prevents lateral displacement of the control plate when cam actuated.

When the hand-wheel 48 is turned, the cam 49, engaging follower 50, forces plate 24 downwardly which through the links 22, pivoted at 23 to said plate 24, forces the members 27-28 outwardly since same with links 20 and cylinders 11 form a pair of parallel motion devices with an included dual toggle mechanism. Springs 29 also as described tend to draw members 27-28 together and thus tend to oppose cam extension of said members.

Obviously the cam-spring action may be oppositely operable by a suitable reversal of parts. Herein the side members are cam extensible and spring retractible and the shoulder members are spring extensible and cam retractible. Both, however, may be of like type, etc.

Surrounding the side members 27-28 and shoulder members 30 and the side member actuating means, the cylinders 11 and the plate 31 is a comparatively light thin rubber-like envelope that is very flexible. This is a sealed bag, 152 and a conduit 53, see Fig. 1, to the base 10 is arranged to supply air pressure to the bag to blow up same. When the pressure is released the bag collapses.

In operation, so far as the foregoing structure is concerned, a shirt is slipped upon the buck and the collar buttoned or the neck band is clipped together. Also, the front adjacent edges are suitably secured. Both of these means are omitted for clearness.

Herein the buck has shoulder extensions 54 to project slightly into the sleeves of the shirt at the shoulder. When the shirt is thus mounted the hand-wheels 48 and 46 are actuated to stretch the shirt sidewardly and vertically so that the shirt then is substantially devoid of wrinkles and creases.

As shown in Fig. 2, each of the side edges, defined by wires 27 and each of the shoulder edges, defined by bars 20, has a comparatively

sharp formation, so that the shirt when pressed is precreased for folding when removed from the buck following the pressing operation. The sleeves, collar and cuffs may be ironed or pressed in the usual manner.

Reference will now be had more particularly to Figs. 3 and 4 and the lower portion of Fig. 1. Therein 110 indicates the main plate and extending upwardly therefrom are two confronting head members 60 and 61. The former is of cavity type, see 60a in Fig. 4. The latter may be of the same type or flat, see also Fig. 4. However, it is notched as at 62 to freely nest and expose the collar form 32. Such notching permits the handwheels 46 and 48 to be positioned outwardly of the head 61 for adjustment and clearance purposes.

Each of the heads is chambered and supplied with steam for heating same and this is continuously supplied during normal pressing operation. These heads, if desired, may be electrically heated.

Head 60 is shown rigid with plate 110 as at 63, see Figs. 3 and 4. Head 61 includes ears 64, pivoted at 65 to ears 66 carried by plate 110. It will be remembered that the buck is slidably associated with piston rods 13 and the lateral ends 16 are pivoted on plate 110 by the ears 15. Herein there extends rearwardly from the buck, see Figs. 3 and 4, and more particularly portions 16 thereof, the arm 166. A spring 67 normally constrains the buck to clockwise tilted position, the extreme tilt being determined by plate carried stop 68. This position is shown in Fig. 3.

Head 61 has ear 69 projecting forwardly and a tension spring 70 between it and the base 110 tends to tilt said head clockwise to the press open position, see Fig. 3. No additional stop is required since the following described structure serves as same.

Plate 110 includes an ear 71 which at 72 pivotally supports the head 73 of cylinder 74. Therein is piston 75 carried by upwardly and rearwardly directed rod 76. This rod extends through the other cylinder head 73a clampingly connected to the other end of said cylinder.

Pivoted at 77 on each side of the head 61 is a lever 78 having one end pivoted at 79 to a cross member 79a, see Figs. 3 and 4, carried by the upper end of the piston rod 76. Each lever 78 extends rearwardly from pivot 77 and includes a catch portion 80 and a cam free end portion 81. Head 60 at each side includes a locking roller 82. Springs 83 connected between levers 78 and cylinder head 73a or the plate 110 if desired, serve to tilt levers 78, 80 and 81 upon pivots 77 when pressure is released from said cylinder. Obviously, two cylinders 74, etc., may be employed when desired.

Referring more particularly to Fig. 3 it will be noted that the heads are separated and the buck can be elevated by air pressure supplied to cylinders 11. A shirt then is buck mounted as previously described and stretched as described. Then buck elevating cylinder pressure is released whereupon the buck lowers by gravity until the buck is positioned between the two heads 60 and 61. Then, and only then, is air pressure supplied to cylinder 74 and rod 76 elevated from the position in Fig. 3 to that shown in Fig. 4 to close the heads about the buck.

In such elevation and near the end thereof the two cam locks, one at each side and straddling head 60, cause portion 80 to seat roller 82. At this time the buck is nested within the heads

and locked therein. When so nested follower 82 is seated.

Only when the heads are thus locked together, with the buck fully enclosed, can pressure be applied to the buck at 53, which expands the buck so that the shirt thereon is pressed against the heated faces of heads 60 and 61 for shirt ironing.

When ironing is completed, pressure is first released from the buck to permit its collapse and then only can pressure be released from the cylinder 74. Springs 83 then become effective to release the lock 80-82 by tilting levers 78 clockwise.

When the press is thus unlocked the head is tilted clockwise to open press position by the spring 70 and by springs 83 if attached to plate 110, see Fig. 3. Only when the parts are so tilted to open press position can air pressure be supplied to cylinders 11 to elevate the buck, as shown in Fig. 3. When the buck is thus elevated each hand-wheel 46 and 48 is twice actuated, that is once in one direction and once in the opposite direction so that the ironed shirt first can be removed and another shirt applied and then stretched, whereupon the aforesaid pressure cycle is repeated.

Pressure supply, etc.

Reference will now be had more particularly to Fig. 7 for the interlock arrangements. In said figure there are illustrated three valve structures, A, B and C, respectively. Valve 90 controls the buck elevating and lowering, valve 91 controls the press locking and unlocking while valve 92 controls the buck inflation and deflation. Each valve structure has connected thereto an air pressure supply line and an exhaust line. Each line is valve controlled and by a valve internal to that structure, the exhaust valve having an exposed stem designated by the primary numeral with subscript d and the intake valve having an exposed stem designated by the primary numeral with subscript c. Herein valve structure 90 has connected to it supply line 99^a and exhaust line 99^b while valve structure 91 has connected to it supply line 91^a and exhaust line 91^b and valve structure 92 has connected to it supply line 92^a and exhaust line 92^b.

A fulcrum on each valve and between said exposed stem portions is designated by the primary numeral with subscript c and pivotally supports a lever designated by the primary numeral with subscript f and laps both valve stems. A spring designated by the primary numeral with subscript g is connected to the lever and constrains the valve lever to exhaust valve open position. Suitable means tilts the lever to selectively actuate the intake or the exhaust valve.

Each valve structure includes a header chamber with which the respective operating line 17, 53 or 89 (the latter to cylinder 74) communicates. The intake and exhaust have valve controlled communication with that chamber as well. When the exhaust valve is closed and intake valve is open, pressure is supplied to the operating line or the pressure therein is retained. When the intake valve in that chamber is closed and the exhaust valve is opened, the pressure in that operating line and all parts connected thereto back to said intake valve is exhausted. With both valves closed and pressure in the operating line, pressure is retained in the cylinder means connected thereto.

Since all valve structures A (90), B (91) and C (92) are substantially similar no specific description of structures B and C is believed necessary except to point out that each valve structure includes valve stems Xc and Xd, fulcrum Xe, arm or lever Xf and spring Xg where X indicates 90, 91 or 92 for the particular structure designated by the latter numbers.

Interlock and automatic control

When the buck is fully lowered, a member 93 carried thereby, see Figs. 1 and 7, contacts lever 91f to open the intake valve in B against the spring 91g and the intake valve spring not shown. Cylinder 74 is charged and the press thereby closed and then locked up.

Only when the press is locked up is lever member 92f actuated by a member 94, see Fig. 4. This supplies pressure for buck inflation and garment pressing. Member 94 may be carried by head 60 as on cross bar 79a. Member 92f is actuated only when the press is locked closed. These two members 93 and 94 are suitably connected respectively by cables 100 and 101 as at 95 and 96 to the lever member 90f so that when members 91f and 92f are in pressure applying or holding positions the lever member 90f is in the exhausting position.

Fig. 8 diagrammatically illustrates the valve control system in the normal position and this is also the pressing position wherein the heads are locked together with the buck nested therein and the buck is inflated.

Fig. 9 shows the position of the valve system when the buck is deflated and the locking arrangement is released and the buck has been elevated for the application of a garment thereto.

It will be recalled that each of the exhaust valves having the stems d is normally constrained to closed position by its respective spring (not shown) and that each of the intake valves having the stem c is normally constrained to closed position by a spring (not shown).

Juxtaposed to these stems is the pivoted member f and each is associated with a biasing spring g that normally constrains the member to effect opening of the exhaust valve associated therewith.

Manual pressure applied to the lever 98 against the spring 99 activates or permits activation of the through link 98, member 90f and by the cables 100 and 101 respectively members 93 and 94. These members 93 and 94 are biased to operative position by their respective springs. This bias is however, overcome when the lever 98 is depressed. The cycle of operation, so far as the control is concerned, is effected as follows.

As previously stated, the buck can never be elevated while it is inflated and, obviously, can not be elevated when the press is locked closed. The buck can not be lowered and locked up unless it is in the deflated condition. So long as the pedal 98 is depressed, the movement of the buck is ineffective to operate members 93 and 94, regardless of the position of the buck. This constitutes a safety feature.

Even if by inadvertence or leakage the buck falls to its lowered position when the pedal 98 is depressed, the members 93 and 94 have been rotated by their springs to their inactive positions and the valves b and c will not be actuated. It is to be understood that Fig. 7 illustrates what might be called a theoretical, neutral position of the valve system which, however, is not normally attained.

To this extent the valve structure 90 is differentially operable with respect to valve structures 91 and 92. The aforesaid interlock is of such character that while lever 90f is in holding or pressure applying position levers 91f and 92f can not be actuated to open their respective intake valves.

It will be apparent that if plate 110 is at floor level, the buck, when elevated, will be about chest height so a shirt can be readily lifted upwardly therefrom and another pulled downwardly thereon. Whenever desired or necessary there may be provided a suitable clamp not shown and the same would be carried by the buck and would be used with a shoulder stretching means herein disclosed.

It is equally obvious that the stretching and creasing members 27-28 and 30 each may be divided. One part then can be positioned exteriorly of the bag or envelope and the other part can be positioned within same or both without or within the same. Also, if desired, all of member 30, as herein illustrated, may be positioned exteriorly of the bag. When such is the case no part of member 30 passes through the bag. When positioned interiorly, however, portion 34 passes through the bag, as described.

The connections at the point where portion 34 passes through the bag and where the shaft 47 enters the bag are rendered leakproof. These stretching members are preferably thin flexible members so that they can conform to the garment as well as crease the same in the pressing operation.

The members 91f and 92f may be maintained in pressure supplying position only so long as the lever member 90f is in exhaust open position. If the lever 90f is moved to pressure supplying position wherein the right end of that member is depressed, the cable is drawn taut to overpower the biasing springs of the members 93 and 94 and they are rotated out of operating position, whereupon the valve biasing springs 91g and 92g function to close the pressure supplying side and open the exhaust side of valves B and C.

In order that the operation of the pivoted member 90f may be facilitated a treadle 98 is connected thereto by a link member 97 so that operable movement of the treadle 98 causes like movement of the member 90f. The treadle 98 and link member 97 are biased upwardly by a spring 99. Inasmuch as this upwardly biased position is the normal position of the treadle 98 it follows that a like position of the member 90f in which the exhaust valve is open and the inlet valve is closed is the normal position of valve A. Thus with the member 90f in its counterclockwise limit or normal position tension on the cables 100 and 101 is reduced so that the biasing springs of the members 93 and 94 position those members to open the pressure supply side and close the exhaust side of the valves B and C with which they are associated. Consequently, then the normal position of the device when under pressure is its locked up position.

Assume now that the device is to be put into operation. The treadle 98 is depressed thereby rotating the member 90f clockwise, which tightens the cables 100 and 101 and rotates the members 93 and 94 into ineffective positions. Upon such rotation the biasing spring 92g causes the valve C to operate to deflate the buck; the biasing spring 91g causes the valve B to exhaust the pressure in cylinder 74, whereupon the heads are unlocked and head 61 moved to open position;

and the clockwise rotation of member 90f causes valve A to supply the cylinders 11 with pressure thereby moving the buck to extended position.

As long as the pedal 98 is maintained in its depressed position fluid pressure cannot be supplied to the buck through valve C or to the cylinder 74 through valve B. Even though the buck descends, through accident or leakage, to its retracted position between the heads, the rocking members 91f and 92f will not be rotated to operate their associated valves to supply pressure as long as the treadle 98 is depressed and the cables 100 and 101 hold the members 93 and 94 in inactive positions.

Now while the treadle 98 is maintained in depressed position, as by a detent not shown, and the buck is extended, a shirt is positioned thereon and adjusted for pressing. The adjustment of the shirt includes the arrangement of the neck band or collar on the collar form and a manipulation of the hand wheels 46 and 48 to position the members 28 and 30 so as to smooth and stretch it as desired. When the adjustment is completed the pedal 98 is released and the spring 99 promptly moves it to its upper limit position. The movement of the treadle is accompanied by like movement of the rocking arm 99f which closes the pressure supply side of valve A and opens the exhaust side thereof whereupon the cylinders 11 are exhausted and the buck descends to its retracted position between the heads 60 and 61.

While the invention has been illustrated and described in great detail in the drawings and foregoing description, the same is to be considered as illustrative and not restrictive in character.

The several modifications described herein, as well as others which will readily suggest themselves to persons skilled in this art, all are considered to be within the broad scope of the invention, reference being had to the appended claims.

The invention claimed is:

1. In a garment press having a pair of confronting separable, heated, garment pressing members, the combination of an expansible and reciprocable buck, means for moving the buck into and out of registration with and from said members, means for locking the members together with the buck included therebetween, means for expanding the included buck into simultaneous engagement with both members for garment pressing, and means operable only when the members are locked together with the buck disposed therebetween for controlling the expanding means.
2. A press of the character defined by claim 1 wherein the expansible buck includes a pressure expansible envelope and a non-conforming supporting, skeleton-type frame.
3. In a garment press having a pair of confronting heated, garment pressing heads relatively movable to open and closed positions, the combination of an inflatable, extensible buck disposed for reciprocation into and out of registration with and between the heads, means for moving said heads towards and away from each other, means for extending the buck for initial stretching of a garment thereon, means for inflating the buck for garment pressing, and means controlling said inflating means and operable only when the deflated buck is disposed between the heads and confined thereby, which is when said heads are positioned immediately adjacent each other.
4. In a garment press having a pair of con-

fronting heated, garment pressing heads, a buck support therebetween at all times, a buck slideable on the support and movable in one direction thereon between said heads and for registration therewith in an opposite direction from between said heads, mechanism effecting pressing pressure between the heads, and a control device for said mechanism for effecting pressing and governed by said buck when the buck is registered between the heads.

5. A press of the character defined by claim 4 wherein additional means is provided for locking the heads together, the said mechanism effecting pressing pressure between the heads including an inflatable structure governed by said control device.

6. A press of the character defined by claim 5 wherein an interlock device is provided between the head locking means and the said mechanism.

7. A press of the character defined by claim 3, wherein locking means secures the heads together with the buck therebetween, and an interlock device is interposed between said locking means and the buck inflating means.

8. A press of the character defined by claim 4, wherein power means is provided to effect buck sliding and an interlock device is interposed between the buck sliding means and the pressing pressure effecting mechanism.

9. A press of the character defined by claim 8, wherein means is provided for locking the heads together, the pressing pressure being effected by inflation, the interlock device preventing locking means actuation until the buck is registered between the heads and preventing inflation until the heads are locked together.

10. A press of the character defined by claim 4, wherein means is provided for locking the heads together and the pressing pressure is effected by inflation, and buck carried members for stretching the garment on the buck prior to pressing.

11. A press of the character defined by claim 4, wherein means is provided for locking the heads together, the pressing pressure being effected by inflation, an interlock device interposed between the locking means and the pressing pressure effecting mechanism, and buck carried members for stretching the garment on the buck prior to pressing.

12. A press of the character defined by claim 8, wherein the buck movably supports members for stretching the garment on the buck prior to pressing.

13. A press of the character defined by claim 9 wherein the buck movably supports members for stretching the garment on the buck prior to pressing.

14. A press of the character defined by claim 4 wherein means is provided for locking the heads together and the pressing pressure is effected by inflation, and buck carrier members for stretching the garment on the buck prior to pressing, the buck being of inflatable character and connected to the pressure effecting mechanism for inflation for pressing.

15. A press of the character defined by claim 14, wherein an interlock device is interposed between the locking means and the pressing pressure effecting mechanism.

16. A press of the character defined by claim 8 wherein the buck movably supports members for stretching the garment on the buck prior to pressing, the buck being of inflatable character and connected to the pressure effecting mechanism for inflation for pressing.

17. A press of the character defined by claim 16 wherein means is provided for locking the heads together and the pressing pressure is effected by inflation.

18. In a garment press, the combination of opposed pressing heads and a pressing buck for positioning therebetween, said buck including at opposite sides outwardly and oppositely extensible members and at the shoulder portions of the buck outwardly and oppositely extensible members and manually operable, buck exposed means for actuating each of said members.

19. A garment press as defined by claim 18, wherein the buck includes a skeleton frame work and an inflatable envelope thereabout and stretchable with said extending means.

20. A garment press as defined by claim 18, wherein the buck includes an inflatable envelope, the opposite sides adjacent the side edges being comparatively thin.

21. In a garment press buck structure the combination of a skeleton framework, including elongated cylinder means, a buck base, and an envelope secured thereto, piston rod support means for the buck, and piston means carried by the support means and slidably associated with the base and cylinder means for sliding the buck relative to the support means.

22. A buck structure as defined by claim 21, wherein there is provided envelope stretching means, manually operable means carried by the framework, and means operable thereby for actuating the stretching means.

23. A buck structure as defined by claim 21, wherein there is provided envelope stretching means, manually operable means carried by the framework, and means operable thereby for actuating the stretching means, the last mentioned means including parallel motion mechanism operatively associated with the cylinder and stretching means for simultaneous stretching at opposite sides of the buck.

24. A buck structure as defined by claim 21, wherein there is provided envelope stretching means, manually operable means carried by the framework, and means operable thereby for actuating the stretching means, the last mentioned means including a cam and follower operable means actuatable in one direction and spring means acting in opposition thereto.
